F. MCCLARENCE

DIAL FOR TELEPHONE SERVICE

Filed Feb. 12, 1923

FIG.1.

FIG. 5.

FIG.4.

FIG. 2.

FIG.3

Inventor:

Francis Mc Clarence.

Attorney: Art Hader

Patented Aug. 4, 1925.

UNITED STATES PATENT OFFICE.

FRANCIS MCCLARENCE, OF HARROW, ENGLAND.

DIAL FOR TELEPHONE SERVICE.

Application filed February 12, 1923. Serial No. 618,625.

To all whom it may concern:

Be it known that I, FRANCIS MCCLARENCE, a subject of the King of Great Britain and Ireland, residing at Harrow, in the county 5 of Middlesex, England, have invented certain new and useful Improvements in and Relating to Dials for Telephone Service, of which the following is a specification.

This invention relates to what are known 10 as "impulse" dials for use in telephone services and particularly to those adapted to automatic telephones, inscribed with numerals, letters or other indications so arranged as to enable the combination of said 15 numerals or indications to be made as will constitute the call of the required subscriber.

It frequently occurs in practice, however, 20 that it is required to use such dials with mixed automatic and manual systems, and an object of the present invention is to permit such use in a simple and inexpensive manner with a single dial.

It also occurs in practice that it is required to restrict the use of the dial or a 25 portion or portions thereof until certain preliminary conditions are fulfilled by the caller, such as the prepayment of the amount of the call in a coin collecting box.

To these ends the external appearance or 30 construction of the dial, the arrangement of the numerals or indications thereon, and general mechanical features are or may be unchanged or may be of any convenient 35 form, but the contact system and circuits are varied for the particular objects in view.

According to the invention, in the use of 40 the dial when requiring prepayment to enable a calling subscriber to be placed in communication with a called subscriber or in the case of a subscriber's meter requiring the 45 registration of the call by mechanical means such as pressing a button, or electrically by means of a current from the exchange, functioning a relay; the usual impulse contacts are normally short circuited or restricted in some way, or the dial is not introduced into the circuit until such payments or operations are effected, as by the necessary coin or coins, press button or electrical current closing or opening contacts 50 which will remove the restrictions, the usual range of indications or so many of them as may be determined being available for such calls.

55 However, should it be desired to allow a signal to pass over the line without prepay-

ment, for example when it is desired to call the exchange for a manual or non automatic communication or to give an alarm for fire, police or other call of an emergency character, then certain of the existing contacts are used or another one or other additional ones are provided which are not normally short circuited or restricted but are always operative and require no payment to be made for 60 their function, these indications being preferably at the beginning or end of the main range of indications so as not to interfere with the general working. Such further or additional contacts may be opened or closed 65 to remove the restriction as by an auxiliary cam or contact device on the dial when moved to calling position, and on resetting of the dial be restored to their normal position, also by said cam being caused to close 70 or reopen the contacts.

From the above description it will be seen that the invention in its broadest functional aspect consists in "unblocking" or 80 normally retaining free for immediate operation a contact or contacts relating to one or more predetermined dial numerals or indications so that said contact or contacts is or are not dependent on the fulfillment of any preliminary condition or manipulation 85 on the part of the user (beyond the ordinary operation of the dial) for such operation.

Thus the operation of calling a number for "automatic" may be the same as at present with prepayment or some other preliminary manipulation to free the required contacts, but the additional facility is provided of being able to immediately ring a 90 "manual" or give an emergency signal when desired by moving the dial to another selected contact or other contacts without prepayment or other preliminary condition.

An embodiment of the invention is represented in the accompanying drawings in 100 which:—Fig. 1 is a front face view of the dial. Fig. 2 is a rear elevation of the dial with the casing removed and showing the majority of the working parts and the mechanism of the present invention applied thereto. Fig. 3 is an end elevation from the 105 left of Fig. 2. Fig. 4 is a detail view of a part hereinafter described and Fig. 5 is a simple circuit diagram showing the application of the invention to one operative system.

The general features of the impulse dial

illustrated in the drawings are of a known or conventional kind and comprise two plates *a* and *b* the outer one *a* which constitutes the dial proper being rotatable and 5 provided with finger holes *a*¹ to expose the numerical indications 1 to 9 and 0 inscribed on the face of the fixed inner plate *b*. The dial *a* revolves with spindle *a*² mounted in the number plate *b*. There is also provided 10 on the latter a stop or abutment *c* to limit the rotation of the outer plate *a* this abutment extending to the front of the dial. Between the dial *a* and number plate *b* is a drum *d* provided on its outer edge with ratchet 15 teeth *d*¹ engaged by a spring *d*² on the dial, and further provided with peripheral teeth which mesh with the teeth of a pinion *e* which extends to the rear of the number plate. At the back of the latter there is 20 coiled about the spindle *a*² a spring *f* by which the dial is returned to normal after rotation and release. On the spindle *e*¹ of the pinion *e* before mentioned is mounted a cam *g* of insulating material such as fibre 25 the enlarged portions *g*¹ of which alternatively engage between a pair of spring contacts *h* as the dial returns to normal position and thus transmits the required number 30 of impulses to automatic selecting mechanism at the exchange according to the distance through which the dial has been rotated. The said spring contacts *h* are carried by a block *h*¹ and suitably insulated at *h*² being extended by conductive strips *h*³ to terminals *h*⁴ connected to any suitable 35 circuits. On the pinion spindle *e*¹ is a toothed wheel *e*² which engages a worm *e*³ on the spindle *e*⁴ of a centrifugal governor housed in a casing *e*⁵ and the springs of 40 which are shown at *e*⁶.

As aforesaid all the above mechanism is substantially known and is adaptable for use in the usual manner for automatic operation when the dial is moved from normal position 45 from any of the indications 1 to 9 to transmit impulses over the line according to the subscriber's number called.

To now turn to the improvement of the present invention a further cam *j* is loosely mounted on the dial spindle *a*² so that when the dial is rotated in the forward direction the end *f*¹ of the spring *f* (which however may be replaced by a pin or other part) and which is passed through the spindle engages one side of said cam and drives it forward. Two additional spring contacts *k* are provided also mounted in the block *h*¹ with suitable interposed insulation *k*¹ and connected by conductive strips *k*² to other terminals *k*³ for circuit connections. The construction is such that in the ordinary operation of the dial between the indications 1 to 9 the cam *j* will not be rotated sufficiently far to engage between the contacts *k* but 60 this will occur only when the dial is rotated

for its full extent from indication "0" the spring end *f*¹ then forcing the cam between the contacts and breaking the circuit until the tenth impulse or until the dial has completed its return movement whereupon 70 spring end *f*¹ acts on the other side of the cam and moves it from between the contacts to again close the circuit.

As an example of a simple dual arrangement with the present invention reference is 75 directed to the diagram of Fig. 5. Here the two cams *g* and *j* are shown the former between the spring contacts *h* and the latter removed from contacts *k*, these contacts being disposed in a circuit *l* which includes 80 in series other contacts *m* contained, for example, in a prepayment coin collecting box *m*¹ and at which the money is held in suspense for an ordinary automatic call. When the contacts *j* and *m* are closed as shown 85 the main lines *X* to the exchange are short circuited. When payment is made by a coin, separating contacts *m* the short circuit is removed and a prepaid automatic call can be made as usual. Again when the contacts 90 *l* are separated by the auxiliary cam *j* the short circuit is also removed and a direct call can be made to the exchange without prepayment for the purpose above specified.

From the above description it will be 95 seen that the following operations may be made and advantages obtained.

In automatic telephone areas where coin 100 collecting boxes of the prepayment type are used, the impulse dial is normally short circuited, and is released for service by placing coins or tokens, in the box. For calls to a manual exchange in the case of trunk, junctions, telegrams, fire, police and service calls, the manual operator, after taking particulars of the call, and sometimes before, refunds the fee to the caller. 105

By means of the improvements described above, the caller is enabled to dial the manual exchange without previously depositing 110 a fee.

The two additional contacts added to the impulse dial are connected in series with the dial short circuiting arrangement of the coin collecting box. To dial a local number the caller places coins or tokens in the coin collecting box in the usual way. If the call is to the manual exchange the caller operates the dial and dials "0" (or other prearranged number or numbers) and the auxiliary cam *j* is forced between its two contacts *k*, this operation breaks the dial short circuit and at the end of the tenth impulse restores it. 115

Many municipal authorities object to the prepayment coin collecting box for all calls 120 contending that it is unreasonable to expect the public to have available a coin in the case of fire, police and ambulance calls and other emergency calls.

Similarly in the case of telephone call 125 130

- 5 meters the impulse dial is inoperative until the caller performs some operation such as pressing a button or a lever to remove the obstruction from the meter, in such cases this operation is a preliminary to the meter registering the call. The improvements do not interfere with the metering of local calls as at present but allow the subscriber to obtain the attention of the manual operator for 10 the extra services mentioned without registering a local call, these extra services being ticketed by the operator and an account rendered periodically.
- 15 What I claim as my invention and desire to secure by Letters Patent of the United States is:—

20 1. In a rotary impulse dial for telephone services having dial indications, contact devices cooperating with same for transmitting impulses over a line, and means for normally restricting the use of said contact devices, the combination of an additional dial indication and co-operating contact devices, and means operated by the rotation of the dial 25 from said latter indication whereby the restriction on the first mentioned contact devices is removed to permit a direct communication to be made over the line.

25 2. In a rotary impulse dial for telephone services, having dial indications, contact devices co-operating with same for transmitting impulses over a line for automatic communications and means for normally short circuiting said contact devices, the combination of an additional dial indication and co-operating contact devices, and means operated by the rotation of the dial from said latter indication whereby the short circuit on the first mentioned contact devices is removed to permit a direct communication to 40 be made over the line.

45 3. In a rotary impulse dial for telephone services having dial indications with a switch device embodying contacts co-operating therewith for transmitting impulses over the

line on dialing from certain of said indications, and means for normally restricting the use of said switch device, the combination of an auxiliary switch device and contacts co-operating therewith adapted to co-operate 50 with other of said indications only when rotating the dial from said other contact, and means operated by said auxiliary switch device for removing the restriction from said first mentioned switch device to permit impulses to be directly transmitted over the line.

4. In a rotary impulse dial for telephone services having dial indications, contact devices cooperating therewith for transmitting impulses over the line, and means for restricting the use of said contact devices normally requiring a preliminary condition to be fulfilled by the caller for transmitting said impulses, the combination of an additional dial indication and additional contact devices co-operating therewith, and means operated by the rotation of the dial from said latter indication for permitting impulses to be directly transmitted over the 70 line without fulfillment of said preliminary condition.

5. In an impulse dial for telephone services the combination of a rotary dial plate, dial indications thereon, a switch device embodying contacts, means for normally short circuiting said contacts, said short circuit being removed by a preliminary operation on the part of the user for transmitting impulses over the line, in combination with an 75 additional dial indication, a second switch device embodying other contacts cooperating therewith whereby on rotating the dial plate from said additional indication, the said short circuit may be removed to transmit 80 85 impulses directly over the line irrespective of said preliminary operation by the user.

In witness whereof I have signed this specification.

FRANCIS McCLARENCE.
